UNITED STATES PATENT OFFICE.

ADOLPH PETZOLD, OF PHILADELPHIA, PENNSYLVANIA, ASSIGNOR TO JOHN H. BROMLEY AND EDWARD BROMLEY, OF PHILADELPHIA, PENNSYLVANIA, COPARTNERS TRADING AS JOHN BROMLEY & SONS.

DESIGN FOR A RUG.

SPECIFICATION forming part of Design No. 35,587, dated January 14, 1902.

Application filed December 17, 1901. Serial No. 86,313. Term of patent 3½ years.

To all whom it may concern:

Be it known that I, ADOLPH PETZOLD, a citizen of the United States, residing at Philadelphia, Pennsylvania, have invented and produced a certain new and original Design for a Rug, of which the following is a full, clear, and exact description, reference being had to the accompanying drawing, forming a part of this specification.

10 My invention has relation to the surface ornamentation of a woven rug; and it consists of the novel design therefor shown in said drawing, in which the essential distinguishing features are a rectangular floral border a 15 with a series of connected line-figures b separating said border from the field center, and in the four corners of the latter are repeats of said line-figures b, diagonally arranged. In the center of the field is a single oval-shaped bunch c of roses and leaves. 20

I claim—

The design for a rug substantially as shown and described.

In testimony whereof I have hereunto affixed my signature this 4th day of December, 25 A. D. 1901.

ADOLPH PETZOLD.
